UNITED STATES PATENT OFFICE.

ROY F. BROWER, OF SYRACUSE, NEW YORK.

SHOE-VENTILATOR.

1,203,694.

Specification of Letters Patent. Patented Nov. 7, 1916.

Application filed June 21, 1916. Serial No. 105,010.

To all whom it may concern:

Be it known that I, ROY F. BROWER, a citizen of the United States, and a resident of Syracuse, in the county of Onondaga and State of New York, have invented a certain new and useful Shoe-Ventilator, of which the following is a specification.

This invention has for its object a ventilator for shoes, which is particularly simple in construction and highly efficient and durable in use, and which is readily attached or applied to the shoes; and the invention consists in the novel combinations and constructions hereinafter set forth and claimed.

15 In describing this invention, reference is had to the accompanying drawings, in which like characters designate corresponding parts in all the views.

Figure 1 is an elevation of this ventilator 20 showing the same as applied to a shoe, the contiguous part of the shoe being shown in section. Fig. 2 is an inverted plan view of a shoe showing the position of the ventilator when attached thereto. Fig. 3 is an 25 enlarged vertical sectional view of my shoe ventilator, the contiguous part of the shank of the shoe being shown in section.

This invention comprises, generally, a part 30 insertible in one end of a perforation in a shoe and formed with an inlet passage having a check valve therein, a part insertible in the other end of the perforation and having a passage therethrough, both parts having heads at their ends which engage or overlie 35 the inner and outer surfaces of the shoe around the perforation.

1 designates the shank of a shoe, and 2 a perforation extending therethrough.

3 is a cylindrical casing having threads 40 for screwing into the perforation 2 of the shank 1, said casing having a head 5 which overlies, and closely fits, the outer surface of the shank around the perforation 2.

6 is a plug having a head 7 at its outer 45 end and a threaded shank for threading into the cylindrical casing 3. The plug 6 is formed with an inlet passage 8 provided with a suitable check valve therein, the passage being formed with an enlargement 9 at its inner end. The bottom of the enlargement is formed conical and constitutes a valve seat for the check valve 10, which is here shown as a ball. The ball is held from displacement through the outer end of the 50 enlargement by inwardly extending shoul-

ders 11 formed by upsetting or distorting the metal at intervals around the outer end of the enlargement, this upsetting being accomplished by indenting as at 12, the margin of the inner face of the plug 6. 60

The inlet passage 8 in the plug 6 terminates near the outer face of the head 7, and is provided with a laterally extending passage 13 branching therefrom, said passage opening through the sides of the plug near 65 the head thereof.

As shown in Fig. 3, the inner end of the threads on the plug 6 have been mutilated or distorted, as at 14, to prevent the entire removal of the same when the inlet passage 70 is opened.

A part 15 having a head 16 similar to the head 5 of the cylindrical casing 3, and having a passage 17 therethrough, is threaded into the inner end of the perforation 2 to 75 prevent the same from closing by collapse of the walls thereof.

Preferably, the ventilator, as seen in Fig. 2, is arranged contiguous to the heel of the shoe at one side of the central portion of the 80 shank 1. The ventilator is applied to the shoe by first making a perforation of suitable size through the shank and screwing the parts 3 and 15 in opposite ends thereof. 85

Owing to the check valve in the inlet passage, the air is drawn into the shoe at each step, but is prevented from returning, and therefore is forced to circulate around the foot and out through the top of the shoe. In damp or muddy weather, the inlet passage 6 90 can be readily closed by turning the plug until the head 7 thereof abuts against the head 5. 90

What I claim is:

1. A shoe ventilator comprising a part insertible in one end of a perforation in a shoe, and formed with an inlet passage having a check valve therein, and a part insertible in the other end of the perforation and having a passage therethrough, the latter 100 part preventing the perforation in the shoe from closing, substantially as and for the purpose described.

2. A shoe ventilator comprising a part insertible in one end of a perforation in a shoe and formed with a head at its outer end and with an inlet passage, having a check valve therein, said passage terminating short of the outer face of the head and having a lateral branch opening through the sides of the 105 110

part in the rear of the outer face of the head, substantially as and for the purpose set forth.

3. In a shoe ventilator, a part insertible 5 in one end of a perforation in a shoe, said part comprising a cylindrical casing having an annular flange at its outer end, and a plug threading into the casing and having a head at its outer end opposed to the flange, 10 and an inlet passage provided with a check valve therein, said passage terminating short of the outer face of the head and having a lateral branch opening through the side of the plug in the rear of the head, substantially 15 as and for the purpose described.
4. In a shoe ventilator, a part insertible 20 in one end of a perforation in a shoe, said part consisting of a cylindrical casing having an annular flange at its outer end, and a plug threading into the casing and having a head at its outer end opposed to the flange, said plug being formed with an inlet 25

passage having an enlargement at its inner end, the bottom of the enlargement constituting a valve seat, and a check valve in the 25 enlargement coacting with the valve seat, said plug being formed with a shoulder located at the outer end of the enlargement in position to partly close the same for preventing removal of the valve, the inlet passage 30 terminating short of the outer face of the head, and having a lateral branch opening through the sides of the plug in the rear near the head thereof, the upper portion of the screw threads on the plug being mutilated 35 to prevent entire removal of the same when the inlet passage is opened, substantially as and for the purpose specified.

In testimony whereof, I have hereunto signed my name, at Syracuse, in the county 40 of Onondaga, and State of New York, this 25th day of May, 1916.

ROY F. BROWER.
